UNITED STATES PATENT OFFICE.

LOUIS H. MAIER, OF NEW YORK, N. Y.

AUTOMATIC MUSICAL INSTRUMENT.

992,367.

Specification of Letters Patent. Patented May 16, 1911.

Application filed November 22, 1909. Serial No. 529,254.

To all whom it may concern:

Be it known that I, LOUIS H. MAIER, a citizen of the United States, and resident of New York city, borough of the Bronx, in 5 the county of New York and State of New York, have invented certain new and useful Improvements in Automatic Musical Instruments, of which the following is a specification.

10 One object of my invention is to provide improved means for controlling pneumatics or bellows used in player pianos, automatic musical instruments, and in other relations, and another object is to provide an improved 15 arrangement of player mechanism with respect to the action of the musical instrument.

My invention comprises novel details of improvement and combinations of parts that 20 will be more fully hereinafter set forth and then pointed out in the claims.

Reference is to be had to the accompanying drawings forming part hereof, wherein,

Figure 1 is a sectional view illustrating 25 my improvements in connection with a primary valve-chest; Fig. 2 is a section on the line 2, 2, in Fig. 1; Fig. 3 is a section on the line 3, 3, in Fig. 1; Fig. 4 is a detail of part of my improved valve; Fig. 5 is a 30 detail plan view of the valve seat; Fig. 6 is a section of the valve and its seat, on the plane of the line 6, 6, in Fig. 5; Fig. 7 is a sectional detail view, on a reduced scale, illustrating the arrangement of several of 35 my improved pneumatics associated with a suction chest; Fig. 8 is a plan view of a modified form of my improved valve; and Fig. 9 is a section on the line 9, 9, in Fig. 8.

Similar numerals of reference indicate corresponding parts in the several views.

In the drawings the numeral 1 indicates any ordinary or suitable bellows or power pneumatic, provided with a port or opening 1^a in one wall, shown having a suitable seat 45 1^b. Pneumatic 1 is mounted upon a chest 2 and spaced therefrom to provide an air passageway 3, as by suitable blocks 4, said passageway permitting air to enter and flow from the pneumatic. Several pneumatics 50 may be placed side by side upon chest 2 at

a suitable distance apart, as illustrated in Fig. 7, suction pipes 5, 5^a being connected with chest 2 in any usual manner. Chest 2 is provided with an opening 2^a in line with each pneumatic 1, and over or in line with each opening 2^a is a diaphragm 6 secured to chest 2 in usual manner. Upon diaphragm 6 is an apertured valve 7, the aperture 7^a of which alines with a corresponding aperture 6^a in diaphragm 6. Valve 7 60 also has a central valve portion 7^b to fit against the inner surface 8^a of seat 8, concentric with its bore 8^b, and valve 7 at its outer under surface is adapted to fit against the concentric seat 8^c. In the arrangement shown 65 valve 7 comprises one or more rings 7^d, say of leather, fitted upon a metal ring 9 having apertures 9^a corresponding to apertures 6^a, 7^a, and alined therewith, the cross bar 9^b being shown provided with a centrally disposed enlargement 9^c to which is attached the valve part or washer 7^b that is adapted to fit against seat 8^a, the under part 7^d of valve 7 being fitted against the diaphragm 6. This arrangement may be adopted as 75 a convenient means to secure the valve to the diaphragm to operate against the opposed seats 1^b and 8. I have shown seat 8 as countersunk at 8^d to provide the concentric seats 8^a, 8^c to assure close fitting of the 80 valve at seat 8, although it will be understood that said seat may be otherwise suitably arranged, such as by having the surface of seat 8 flat, whereby under one condition valve 7 will close opening 1^a at seat 1^b and 85 under another condition the valve will close the opening at seat 8 through the openings 6^a, 7^a. The metal piece 9 is provided for purpose of rigidity and to afford a central part 9^e against which a plunger or stem 10 90 is adapted to bear, which plunger is guided in the bore 8^b of seat 8. Seat 8 may be supported by a bar or extension 8^e secured to chest 2. Plunger 10 extends into chest 2 and bears against diaphragm 11 which covers the 95 recess 12 communicating with port 13 of bore or conduit 14 of chest 2. The devices above described may be connected with the appropriate valves of any well known primary valve-chest construction 17 from which 100

- pipes 18 lead to the tracker. Suction for chest 17 will be maintained through pipe 19, to a power bellows in any well known manner.
- 5 Suction being maintained in chest 2, as through pipes 5, and 5^a, and in chest 17 through pipe 19, and the music sheet closing the orifices in the tracker, diaphragms 6 will be drawn to cause valves 7 to close upon 10 seats 8 to uncover seats 1^b, and atmospheric air will pass through channel 3 into the several pneumatics 1, as shown at the left in Fig. 1; when an orifice at the tracker is uncovered the air passing through the corresponding tube 18 raises the valve shown at 17^a and atmospheric air then passing under said valve through tube 15^a causes the corresponding diaphragm 11 to bulge outwardly, as at the right in Fig. 1, thereby pushing 15 upon stem 10 which raises valve 7 from seat 8 and closes valve 7 against seat 1^b, and then the suction in chest 2 will draw the air from the corresponding pneumatic 1 into said chest through the opening in valve 7 and 20 diaphragm 6 causes such pneumatic to collapse, atmospheric air thus being shut off from the pneumatic by the seating of valve 7 against seat 1^b. As soon as such orifice at the tracker is closed by the music sheet, and 25 air cut off from the corresponding pipe 18, valve 17^a will close, which is permitted by the ordinary bleed 17^b, and the air then being pulled through tube 15^a from under diaphragm 11 at the right in Fig. 1 causes such 30 diaphragm to be drawn down, and thereupon the suction in the corresponding chest 2, by drawing upon diaphragm 6, pulls valve 7 from seat 1^b and upon seat 8; thus shutting off suction into chest 2 through valve 7 and 35 permitting air from channel 3 to pass into the corresponding pneumatic 1 through opening 1^a, whereupon said pneumatic will expand. Thus, by the use of the double-acting 40 valve 7 in connection with the opposed seats 1^b and 8 I am enabled to permit atmospheric air to enter the pneumatic when the valve moves in one direction and to shut off such air and suck air from the pneumatic when 45 the valve moves in the opposite direction, 50 effected by the simple back and forth movement of the apertured valve, the arrangement being such that when the apertured valve moves away from seat 1^b the aperture no longer serves as a passage for air, as it is 55 then firmly seated upon seat 8, and yet atmospheric air passes freely from channel 3 over valve 7 to opening 1^a. The freedom of movement of the valve 7 by being mounted upon diaphragm 6 reduces friction of air 60 flowing into the pneumatic, as the opening 1^a can be relatively large, and has direct communication with the atmosphere, and the suction from the pneumatic is also directly 65 through such relatively large opening 1^a and the relatively large aperture or apertures in valve 7. Such direct action of the air overcomes the requirement of the usual ports and channels containing angles which set up 70 resistance to the free flow of the air. It will be understood that, by reason of the suction in ordinary piano players being relatively light, the action of the air in accordance with my invention will give increased efficiency and freedom of vibration of the movable part of the bellows. 75
- Where the primary valve arrangement 17 is not used and the tubes 15, 15^a are connected directly to the tracker, the same operation of my improvements will take place as described with respect to Fig. 1, but in such 80 case a suitable bleed will be provided, between chest 2 and each pipe 15, 15^a, such as represented at 17^b.
- In Figs. 8 and 9 I have shown a modification of the means for positively operating 85 valve 7. In this case seat 8 is not required to have the concentric part 8^a, stem 10 being dispensed with, and the metal ring 22 arranged similarly to ring 9, but provided with extensions 22^a bent toward and adapted 90 to coact with diaphragm 11. In this case when diaphragm 11 bulges toward seat 8, valve 7 will be lifted from said seat, and when diaphragm 11 bulges away from seat 8 valve 7 will be seated thereon. Diaphragm 95 6 is provided with opening 6^a and valve 7 has opening 7^a as before described, but in this case there is no requirement for the parts 9^b, 9^c. In Fig. 9 seat 8 is shown recessed to afford perfect contact of valve 7 at 100 its outer edge 8^c. The pneumatics 1 may be arranged to operate the action of the piano or other musical instruments in any suitable or well-known manner.
- Having now described my invention what 105 I claim is:—
1. The combination of a pneumatic provided with an opening, a chest having an opening, an apertured diaphragm and a seat adjacent said opening, an apertured valve in 110 position to be operated by the diaphragm, the apertures of said diaphragm and valve registering, the valve registering with said seat when in one position to close the chest opening, said valve causing communication 115 between the pneumatic and the chest when off said seat.
  2. The combination of a pneumatic provided with an opening, a chest having an opening provided with a seat, an air channel between the pneumatic and the chest communicating with the atmosphere, an apertured valve between the chest and pneumatic, and a flexible diaphragm movably supporting said valve, said valve normally 120 closing the second named opening and un-

- covering the opening of the pneumatic in one position, said valve coöperating with the opening of the pneumatic to cause communication between the pneumatic and chest in another position. 5
3. The combination of a pneumatic, a chest, opposed openings in the chest and the pneumatic, and an apertured valve and diaphragm between said openings, the apertures of the diaphragm and valve registering and providing communication between the pneumatic and chest through the valve while in one position and at the same time shutting off the flow of atmospheric air to the pneumatic, the diaphragm flexibly supporting said valve. 10
4. The combination of a chest, a pneumatic mounted thereon, an air channel between the chest and pneumatic, and an apertured valve and diaphragm interposed in said channel, the apertures in said valve and diaphragm registering, said chest having an opening leading to the air channel, the diaphragm being located at said opening and flexibly supporting said valve, and means to cause closing of said opening when the valve is in one position and at the same time cause communication between the pneumatic and the channel. 15
5. The combination of a pneumatic, a chest, a valve device between the pneumatic and chest comprising an apertured valve and an apertured diaphragm, said apertures registering, said valve and diaphragm permitting communication between the pneumatic and chest when in one position and permitting the flow of atmospheric air to the pneumatic when in another position, the diaphragm flexibly supporting said valve. 20
6. The combination of a pneumatic, a chest, a valve device between the pneumatic and chest comprising an apertured valve and an apertured diaphragm, said aperture registering, said valve and diaphragm permitting communication through the valve between the pneumatic and chest while in one position, said valve permitting communication between the pneumatic and atmosphere while in another position and at the same time closing communication between the chest and atmosphere, the diaphragm flexibly supporting said valve. 25
7. The combination of a pneumatic provided with an opening, a chest having an opening, and a valve and diaphragm having registering apertures to control said openings successively, the diaphragm flexibly supporting said valve. 30
8. The combination of a pneumatic having an opening, a chest having an opening, and a valve and diaphragm having registering apertures, spaced between said openings and movable therebetween to control one of
- said openings while in one position independently of the other, the diaphragm flexibly supporting said valve. 65
9. The combination of a pneumatic having an opening, a chest having an opening, said openings having seats, a diaphragm adjacent said second named opening and provided with an aperture, an apertured valve carried by said diaphragm, the space between said seats being greater than the thickness of the valve permitting the valve to close upon one of said seats independently of the other. 70
10. The combination of a pneumatic having an opening, a chest having an opening, an apertured valve, a diaphragm carrying said valve, a diaphragm at a distance from the first named diaphragm, means for operating said valve by the second named diaphragm, and means to operate the last named diaphragm. 75
11. The combination of a pneumatic provided with an opening, a chest having an opening, an apertured valve, a diaphragm carrying said valve, a diaphragm at a distance from the first named diaphragm, a member interposed between said diaphragms, and means to operate the second named diaphragm. 80
12. The combination of a pneumatic having an opening, a chest having an opening, said openings having seats, an apertured diaphragm adjacent said second named opening, and an apertured valve having members located at opposite sides of the diaphragm to coact with said seats respectively. 85
13. The combination of a pneumatic having an opening, a chest having an opening, said openings having seats, an apertured diaphragm adjacent said second named opening, an apertured valve having members located at opposite sides of the diaphragm to coact with said seats respectively, a frame adjacent said valve provided with a cross piece, a stem coacting with said cross piece, a diaphragm coacting with said stem, and means to operate said diaphragm. 90
14. The combination of a pneumatic, a chest, a valve device between the pneumatic and chest comprising a diaphragm and valve having registering apertures to control communication between the pneumatic and chest, said valve also controlling communication between the pneumatic and the atmosphere, the diaphragm flexibly supporting said valve. 95
15. The combination of a pneumatic provided with an opening, a chest having an opening provided with a seat, an apertured valve to coact with the first named opening and with said seat, means movably and flexibly supporting said valve, said valve supporting means and valve closing the 100
- 110
- 115
- 120
- 125

opening in the chest in one position, said apertured valve permitting communication between the pneumatic and chest in another position.

- 5 16. The combination of a pneumatic having an opening, a chest having an opening, a diaphragm and valve having registering openings to control the first named openings, a movable member independent of said 10 diaphragm, means for operating said valve

by said movable member, and means to operate said movable member, the diaphragm flexibly supporting said valve.

Signed at New York city, in the county of New York, and State of New York, this 20th 15 day of November, A. D. 1909.

LOUIS H. MAIER.

Correction in Letters Patent No. 992,367.

It is hereby certified that in Letters Patent No. 992,367, granted May 16, 1911, upon the application of Louis H. Maier, of New York, N. Y., for an improvement in "Automatic Musical Instruments," an error appears in the printed specification requiring correction as follows: Page 3, line 43, for the word "aperture" read *apertures*; and that the said Letters Patent should be read with this correction therein that the same may conform to the record of the case in the Patent Office.

Signed and sealed this 25th day of March, A. D., 1913.

[SEAL.]

C. C. BILLINGS,

Acting Commissioner of Patents.
